UNITED STATES PATENT OFFICE.

WALTER WILLMOTT, OF TORONTO, ONTARIO, CANADA.

ART OF STAMPING BOOK-COVERS AND THE LIKE.

1,320,950

Specification of Letters Patent.

Patented Nov. 4, 1919.

Application filed April 16, 1919. Serial No. 290,506.

To all whom it may concern:

Be it known that I, WALTER WILLMOTT, of the city of Toronto, in the county of York, Province of Ontario, Canada, have invented certain new and useful Improvements in the Art of Stamping Book-Covers and the like, of which the following is a specification.

This invention relates to a method of producing stamped or depressed gilt lettering or designs more economically than by the present method in which metal leaf is employed. In producing stamped lettering or designs with metallic facing, the surfaces on which the design is to be stamped are sized or coated with powdered rosin or other thermo-plastic adhesive. Metal leaf is then laid over the parts and the design impressed with a hot die or stamp. This process is expensive as the laying of the leaf in place takes considerable time as also does the removal of the surplus leaf after the impression has been made. Further, there is a great waste of the metal leaf since sheets of leaf must be used of the extreme dimensions of the design, whereas the actual area of the parts of the design is usually very considerably less than the area of the sheet of metal leaf employed.

In carrying out my process I use metallic powders and use for each impression only so much of the powder as is necessary to properly cover the impressed surfaces of the design. In carrying out my process I first slightly grease the dies or stamps and then apply thereto a coating of a metallic powder such, for example, as ordinary bronze powder. This may be effected by bringing the dies in contact with a flat surface on which the bronze powder is thinly spread.

The dies, which are heated in the ordinary manner, are then brought into contact with the surface to be stamped, which has been suitably sized or powdered with rosin or other thermo-plastic adhesive. As the grease on the dies is only sufficient to enable them to pick up the bronze powder, but not to permeate the powder picked up, the powder readily transfers to the surfaces of the design which are rendered sticky by the heat of the dies.

The pressure employed in stamping the design gives the deposited metallic powder a burnished surface equal to that obtained

with the best leaf. No difficulty is experienced with the slight greasing of the dies employed in picking up enough powder to completely and evenly cover the surfaces of the design.

The process may be carried out with many different forms of apparatus, a simple outfit being shown in the accompanying drawings in which—

Figure 1 is a front elevation of part of a stamping press;

Fig. 2 a plan view, on a larger scale, of the work-carrying plate; and

Fig. 3 a side elevation, on the same scale as Fig. 2, of part of the press showing the work carrying plate in position.

In the drawings like numerals of reference indicate corresponding parts in the different figures.

In Fig. 1, 1 is the movable platen or bed and 2 the fixed platen carrying the dies 3. The press is of ordinary construction and will be provided with any suitable means for operating the movable platen and for heating the fixed platen to heat the dies.

The case to be stamped is fitted on a plate 4 provided with suitable stops 5 to position the case. The bed of the press is provided with stops 6 to aid in positioning the plate 4 below the dies. The plate carries the counter dies 7 with which the dies 3 co-operate. Along the front edge of the plate 4 is located the absorbent pad 8 which is saturated with oil or grease.

The first step in the process is to draw the pad 8 over the faces of the dies. A plate carrying a thin layer of bronze powder is then placed in the press and the dies brought into contact with it. The dies are then lifted and the plate 4 carrying a case 85 inserted in the press. An impression is then made and the dies raised. When the plate 4 carrying the stamped case is withdrawn by hand to enable the operator to remove the finished case and place a blank 100 case in position, the pad 8 is drawn over the dies which greases them ready for the next operation.

With other apparatus, the precise mode of operation would be varied, but in every case, the sequence of operations of greasing the dies, applying powder thereto, and then making the impression will be adhered to.

What I claim as my invention is:

1. A process for the purpose described 114

1,820,950

2

which consists in slightly greasing the face of a die; applying a metallic powder thereto; and impressing with the die an impressionable surface with an adhesive.

5 2. A process for the purpose described which consists in slightly greasing the face of a heated die; applying a metallic powder

thereto; and impressing with the die an impressionable surface coated with a thermo-plastic adhesive.

Dated at Toronto this 24th day of March,
A. D. 1919.

WALTER WILLMOTT.

It is hereby certified that in Letters Patent No. 1,320,950, granted November 4, 1919, upon the application of Walter Willmott, of Toronto, Ontario, Canada, for an improvement in "The Art of Stamping Book-Covers and the Like," an error appears in the printed specification requiring correction as follows: Page 2, line 4, claim 1, after the word "surface" insert the word *coated*; and that the said Letters Patent should be read with this correction therein that the same may conform to the record of the case in the Patent Office.

Signed and sealed this 23d day of December, A. D., 1919.

[SEAL.]

M. H. COULSTON,
Acting Commissioner of Patents.
